UNITED STATES PATENT OFFICE.

MATTHIAS KOCH, OF MONTREAL, CANADA.

MACHINE FOR FOLDING OR PLAITING PAPER.

SPECIFICATION forming part of Letters Patent No. 658,919, dated October 2, 1900.

Application filed September 19, 1899. Serial No. 731,629. (No model.)

To all whom it may concern:

Be it known that I, MATTHIAS KOCH, of the city of Montreal, in the district of Montreal and Province of Quebec, Canada, have invented certain new and useful Improvements in Machines for Folding or Plaiting Paper; and I do hereby declare that the following is a full, clear, and exact description of the same.

My invention relates particularly to machines for plaiting paper for carpet-lining, although it may be applied to advantage wherever paper or other easily-manipulated sheet material is to be folded or plaited.

The object of my invention is to provide a machine that will do a greater variety of work than machines heretofore used for this class of work, one that will have fewer parts, and consequently be less complicated, and be able to turn out a better class of work than has been possible heretofore.

The invention may be said briefly to consist in mounting a pair of reciprocating blades to reciprocate in diagonally-intersecting planes, each of which intersects in turn a horizontal plane extending between a pair of feed-rollers, upon each one of which one of said blades yieldingly impinges. A series of carrier-rolls equal in number to the thicknesses or layers it may be required that the finished lining consist of are mounted at the rear of the machine, each roll carrying a length of paper. A conveyer extends from these feed-rollers to an inclined table hinged at its rear end to the frame of the machine and resting at its forward end upon the receiver-roll, which receives and winds upon itself the folded paper. A roller extends transversely of the conveyer in a position to bear upon the folded paper as it is being conveyed, and a series of strips having one side coated with adhesive substance is fed between said roller and the work, with its adhesive side in contact with the latter. I also provide a measuring device for measuring the work as it passes through the machine. This measuring device consists of a measured and marked strip which passes from a carrier-roll to and beneath the last-mentioned roll and around the receiver-roll to a take-up roll.

Other novel features of construction are embodied in my invention; but for full com-

prehension thereof and of the foregoing reference must be had to the accompanying drawings, forming a part of this specification, in which like symbols indicate the same parts, and wherein—

Figure 1 is a left-hand side elevation of my improved machine looking from the front; Fig. 2, a view of the right-hand side of the machine; Fig. 3, a rear view of the machine with the carrier-rolls removed. Figs. 4, 5, and 6 are detail views illustrating the means for reciprocating the knives and the means for intermittently causing the lower knife to impinge through the paper upon the upper roll; Fig. 7, a detail plan view of one roll for carrying the paper to be plaited, and Figs. 8 and 9 are detail views of the receiver-roll.

The frame of my machine has at each side thereof a laterally-projecting wing-piece constituting tables *b* and *c*, and the bolts that secure the tables in place extend through the offset lower ends of a pair of vertical bearing-plates *d*, secured to the sides of the top of the base and having their forward ends and central portions vertically elongated and each in the form of a **U**, as at *f* and *g*, respectively. The trunnions of the upper and lower feed-rolls *h* and *i*, respectively, rest in the **U**-bearings *f*, and the outer or compressor rolls *j* and *k* of the conveyer rest in the **U**-bearing *g*. The upper feed-roll *h* is caused to bear yieldingly upon the work passing between it and the lower roll by a helical spring *l*, while the upper compressor-roll *j* is caused to bear with uniform but adjustable pressure upon the work by a set-screw *m*. A pair of small rolls *e* are mounted in the bearing-plates in close proximity to the feed-rolls, and a series of separate loops of wire *n*, independent of one another, take over said small rolls and the compressor-rolls *j* and *k*. The upper lengths of the loops which take over the roll *k* and its corresponding small roll pass through perforations in and run along a table *o*, extending from the roll *k* to the feed-roll *i*, as shown particularly in Fig. 2. The bearing-plates have horizontal extensions, and the portion of said plates in rear of the feed-rolls *h* and *i* are horizontal, and each has a pair of horizontal bars *p*, supported thereon a sufficient distance above the bearing-plates and one another to provide horizontal guideways

q and r, respectively, for the cylindrical carrier-bars s' and t' of the upper and lower plaiting-knives s and t, respectively. These plaiting-knives are each made up of a number of sections u, connected together at their forward ends by a cross-bar v and at their ends to their carrier-bars, and they are of sufficient length to project when in their foremost position to within a short distance of the vertical plane of the axes of the feed-rolls.

In order to form a box-plait, the plaiting-knives must alternately come into sufficiently-tight contact with the paper from which the lining is being formed to move said paper forward with them, the paper forward of the knives meanwhile being held by the feed-rolls against movement, and then each knife must move back out of the path of the other knife. The upper knife is caused to perform its function by means of a bell-crank lever w, formed in one with a sleeve x, secured by a set-screw rigidly upon the right-hand end, looking from the front of the carrier-rod s'. One arm of this bell-crank lever has a link 150, rigidly and adjustably connected at one end thereto by a bolt 2, while the other end thereof is yieldingly connected by a retractile helical spring 3 to a stationary part of the frame. A shaft 4 extends transversely from side to side of the machine and bears in the bearing-plate d. A large gear-wheel 5 is mounted rigidly upon the end of said shaft adjacent to and overlapping the lower arm of said bell-crank lever w, which is tripped upon by an inwardly-projecting pin 6, carried on the inside face of said gear 5, near the periphery thereof, thereby causing the knife s to impinge upon the paper therebetween and the lower feed-roll.

In order to reciprocate the upper knife to and from the lower roll, an eccentric 7 is mounted rigidly upon the shaft 4 between the bearing-plates, and the collar of this eccentric is connected by a link 8, Fig. 4, to the lower end of a lever 9, mounted rigidly upon a shaft 10, which is in turn mounted at its ends in the said bearing-plates, while a pair of single-arm levers 151 are also rigidly mounted upon said shaft 10, one near each end thereof, and the upper ends of these levers are pivotally connected by links 12 to the carrier-bar s' of the upper knife. It is obvious that the rotation of the shaft 4 will oscillate the lever 9 and through said lever rock the shaft 10, which will in turn oscillate the levers 151 and through the link 12 reciprocate the upper knife s.

The lower knife has a reciprocal movement toward and from the feed-rolls, imparted thereto by the rotating shaft 4 through a gear 13, mounted rigidly upon said shaft and intermeshing with a gear 14, mounted rigidly upon one end of a stub-shaft 15, supported in a pillow-block 16, secured upon the top of the base. A crank 17 is mounted upon the other end of said stub-shaft and is connected by a link 18 to the lower end of a lever 19, mount-

ed rigidly upon a shaft 20, rotatably supported in socket-bearings formed in the inside faces of said bearing-plates d. A single-arm lever 21 is also mounted at one end rigidly upon the shaft 20, and the upper end of this lever 21 and the upper end of the lever 19 are each connected by a short link 22 to the carrier-bar t' of the lower knife t. This lower knife is caused to impinge upon the paper between it and the upper feed-roll (alternately with the impingement of the knife s upon the lower feed-roll) by a cam 23, mounted upon the shaft 4 outside of the bearing-plate d and near the left-hand end thereof, looking from the front of the machine. This cam acts upon a block 24, formed in one with an arm 25, fulcrumed to the bearing-plate, and causes it to at times assume a position to act as a cam to impart the required upward oscillatory movement to the knife through an antifriction-roller 26, mounted upon a stub-spindle 27, adjustably secured to the slotted outer end of an arm 28, through which slot the screw-threaded diminished inner end of said spindle takes and receives a nut 29 thereon. This arm 28 has its inner end increased in width, as at 30, to take over the end of the bar t', to which it is adjustably secured by a pair of set-screws 31, the latter adjustment being required to take up the wear between the cam 23 and block 24 and block 24 and the antifriction-roller 26, while the adjustment of the roller longitudinally of its carrying-arm 25 is to regulate the extent of movement of knife t in its upward swing upon the upper feed-roll, the extent of movement being of course increased or diminished according as the roller is adjusted toward or from the bar t'.

I prefer to make the carpet-lining, as heretofore, from three independent sheets or lengths of paper, because in that way it is easier manipulated than when made from a single length of heavy—say three-ply—paper, although, if desired, single or two or more lengths can be manipulated. In order to use three lengths, I mount three carrier-rolls 33, 34, and 35, respectively, in bearings upon a rearwardly-extending frame 36, bolted to the under side of the tables b and c. The lengths of paper are taken from the carrier-rolls under a guiding-bar 37 and carried over a rod 38 (which keeps it from sagging) between the plaiting-knives to the feed-rolls.

To coat one side of several strips of paper with adhesive substance—paste, for instance—and attach said strips to the plaited paper to bind together and prevent the plaits spreading, I mount, preferably, four carrier-rolls 54, each carrying a rolled length 55 of paper in a strip upon a frame 56, secured rigidly to the front of the machine. These paper strips are taken from their carrier-rolls over a bar 57, mounted rigidly in a frame 58, bolted to the main frame of the machine, as at 59. This frame 58 has a diagonally upwardly projecting portion 61, in which are

supported a pair of rolls 62 for feeding the strips 55, these rolls being carried in bearing-blocks 63, taking into the parallel sides of said frames, and the upper roll being caused to bear yieldingly upon said lower roll by means of an expandable coiled spring 64, bearing between each of the bearing-blocks 63 of said upper roll, and a cap 65, extending across the open upper end of each of said parallel sides. A shaft 66, having four rollers 67 rigidly mounted thereon, bears in said frame 58, with the rollers 67 dipping into an adhesive compound, such as paste, carried in a dish 68. The strips are taken over these "pasting-rollers," as they may be termed, to and beneath a pressure-roller 69, resting in slots 70 in the main frame of the machine, between the upper and lower lengths of the upper wire loops n of the conveyer, at which point said strips become attached to the plaited paper and travel along therewith through the compressor-rolls j and k . An inclined table 72 is pivotally connected at its rear end on a line with the horizontal table of the conveyer and rests at its forward end upon a receiver-roller 73, mounted in the upwardly-turned forward ends of a pair of diagonal arms 74, bolted at their rear ends to the tops of the tables b and c . This roller, which is of peculiar construction, as will be presently set forth, has a pulley 75 mounted rigidly upon one end thereof, as shown, and this pulley is operatively connected by a crossed belt 76 to a pulley 77, mounted rigidly upon the corresponding end of the shaft 4, while this latter shaft is driven by a main driving-shaft 78, bearing in a pillow-block 79, bolted to the table b , and having mounted thereon loose and tight pulleys 80 and 81 and a gear 82, intermeshing with the gear 5, mounted upon the adjacent end of the shaft 4. A fly-wheel 84 is mounted upon the end of said shaft 78 to cause the machine to run evenly. The receiver-roller 73, above mentioned, is of wood, having an axial groove 85 and a pair of ferrules 86 and 87 on its ends, 86 having a socket 88 in line with the groove 85, and 87 being tapped to receive a set-screw 89 for securing a small clamping-plate 90 over the adjacent end of the groove 85. The end of the completed lining is secured to this roll by a length of stiff wire 91, which is inserted at one end in the socket 88 and stretched over the end of the lining and pressed into the groove 85, thus firmly fixing said end of the lining in said groove, where it is held against displacement by the clamping-plate 90. When the desired quantity of carpet-lining—say fifty yards—has been completed and rolled upon the roller, the belt 76 is removed from the pulley 75, the roller lifted from its bearings, the screw 89, and with it the clamping-plate 90, loosened, the wire withdrawn from the roller, and the roller from the rolled lining.

The tension of the belt 76 is regulated by means of a tension-sheave 120, carried by an

arm 155, fulcrumed upon a stationary trunnion 122, upon which a ratchet-wheel 156 is rigidly mounted, the arm 155 carrying a spring-pawl to engage the ratchet-wheel and retain the arm and through it the tension-sheave in any position to which it may be moved.

The carrier-rolls at the rear of the machine are also of peculiar construction and provided with a pair of axially-bored conical bushings 92, which are forced into the ends of the axial opening of each rolled length of paper from which the lining is to be made. A rod 93 takes through these bushings, and the bushings are secured against displacement from the rolled paper by set-screws 94, taking through said bushings and bearing upon the rod 93, while the rod rests in the bearings, wherein it is held against longitudinal movement by a collar 95 at one end and a tension-wheel 96 at the other. This tension-wheel is in the form of a sheave, over which takes a cord 97, secured at one end to the floor of the building and weighted at its other end, as at 98.

The feeding of the paper is effected, after it has been plaited, by means of an oval cam 100, eccentrically mounted upon the shaft 4 outside of a bearing-bracket 101, (in which it bears,) secured upon the table c . This oval cam acts upon an antifriction-roller 153, mounted in the end of lever 102, fulcrumed upon a short shaft 103, mounted in a bearing 104, secured upon said table c , this lever being, through its antifriction-roller, kept yieldingly in contact with the cam 100 by a retractile coiled spring 105, connected at one end thereto and at its other end to an arm 104, bolted to the top of the table c . A spring-pawl 106 is carried by this lever 102 in a position to engage and intermittently rotate a ratchet-wheel 107, mounted rigidly upon said stub-shaft 103, upon which is also mounted a gear 108 and an oscillatory bracket, the gear being rigidly mounted, while the bracket is loose. This bracket is oscillatory only for purpose of adjustment and is in the form of a slotted quadrant 109, having a downwardly-projecting longitudinally-slotted arm 110. The bearing 104 is formed with an arm 111, transversely slotted to carry a bolt 112, which projects through the slot in the quadrant and has a tightening-nut 113 thereon, while a bolt 114 takes through the slot in arm 110 and has a set-nut 115 thereon and carries a gear-wheel 116, which intermeshes with the gear 108. The gear-wheel 116 in turn intermeshes with the lower one of a pair of gear-wheels 117, mounted upon the main feed-rolls, the upper feed-roll having a gear 118 mounted at one end thereof outside of its gear 117, while intermediate the gears 118 and 117 a pulley 119 is mounted upon the upper roll and is connected by a belt 120 to a sheave mounted rigidly upon the upper conveyer. A gear-wheel 121 is mounted at the opposite side of the machine to that at which

said gears 117 and 118 are located upon the end of the shaft of the pasting-rollers and intermeshes with a gear-wheel 122, mounted rigidly upon the lower of the strip feed-rolls, 5 on the opposite ends whereof a pair of intermeshing gear-wheels 123 are mounted.

The gear 118 for transmitting rotary power from the feed-roll-operating gears to the rolls for feeding the adhesive strips is of greater 10 diameter than the gear for operating the feed-rolls in order to cause the main feed-rolls to travel at a less speed than the strip-feed rolls, and thereby cause the strip-feed rolls to feed a greater length of the binding-strip than 15 that of the plaited paper fed by the main feed-rolls. This has the effect of imparting a springy nature to the completed lining, while the oval cam is mounted eccentrically—that is to say, nearer one end thereof than the 20 other—to cause the work to be fed a greater distance after the lower knife has acted than after the upper knife has acted. This is necessary for the reason that after the lower knife has acted the work must be fed a distance equal to one complete plait and the 25 space between said plait and that next following, while after the upper knife acts the work must only be fed a distance equal to one complete plait.

30 In order to determine the output of the machine, I mount a rolled length of measured tape 125 upon a roller, mounted in turn in the end of a bracket-arm 126, secured to the frame 58, this tape being drawn from its roll 35 by the rolls 63 for feeding the paper strips and is taken at one side of the pasting-rollers 67, over the edge of the dish 68, beneath roller 69, over receiving-roller 73, and beneath a guiding-roller 127 to a winding-roller 128, mounted upon a shaft 129, which also has a sheave 130 mounted thereon and operatively connected by a belt 131 to a sheave 132, mounted upon the adjacent end of stub-shaft 103.

The operation of my improved machine is, 45 briefly, as follows: The ends of the lengths of paper from which the lining is to be made are first inserted between the feed-rolls, and the machine then is brought into motion by slipping the driving-belt from the loose to the 50 tight pulley. I have found that the knives will not slip if each acts upon the paper at an angle greater than forty-five degrees relatively to the paper upon the roll. During a complete cycle of operation one of the knives— 55 say the upper—moves forward to within a short distance of the work and is then lowered into contact with the paper, causing it to bear upon the said roll and the knife by friction to grip the paper, the knife continuing in its forward movement pushing the paper forward and causing the portion between the knife and the feed-rolls to fold. The pin 6 upon the gear-wheel 5 having passed the lower arm of the bell-crank lever w , the spring 60 6 causes the knife to move out of the path of the lower knife. The work is then fed during the dead-centering of the eccentric 7 and

crank 17 with their links, the upper knife having reached and simultaneously the lower commences to perform the functions just described with relation to the upper knife, except that the lower knife is caused to first push the paper along the surface of the upper feed-roll, and the pressure of the lower knife upon the upper feed-roll is caused by the anti-friction-roller 26 of arm 28 running along the upper cam-face of the arm 25 and block 24, and the pressure is relieved from the lower knife, and the latter is moved out of the path of the upper knife by the cam releasing the 80 said intermediate parts and allowing the knife to drop by gravitation.

In order to produce a springy carpet-lining, I cause the feed mechanism of the binding-strips to feed a greater length than that of the complete lining fed from the plaiting-knives by the main feed-rolls, as before mentioned. My reason for doing this is because the main feed-rolls must compress the plaits to feed them, and if a length of binding-strip 90 were fed equal to the length of completed compressed lining said lining would be too flat to have a springy nature. Feeding a greater length of binding-strip in proportion connects the plaits together after they have 95 opened out to a certain extent, thus imparting a springy nature to the completed lining.

I have found that by constructing and operating a machine according to the foregoing the plaits will be made more uniform and that 100 their uniformity will be retained, while by consulting the measuring-strips the length of the completed lining can at any time be ascertained at a glance.

An important feature of this invention is 105 that by removing either of the knives a single plait can be formed, and by adjusting the feed plaits of any desired length can be formed.

What I claim is as follows: 110

1. In a machine for folding or plaiting paper, the combination with the frame of the machine, of a pair of feed-rollers mounted one above the other in said frame; a pair of horizontal guideways formed one above the other at each side of said frame and extending toward said rollers; a pair of bars extending parallel to said rollers and supported at their ends in said guideways; a plaiting-knife secured rigidly to said upper bar and projecting toward the lower feed-roller; a second plaiting-knife secured rigidly to said lower bar and projecting toward the upper feed-roll; a shaft 10, rotatably mounted in the frame of the machine; a pair of levers 151 mounted rigidly at their lower ends upon said shaft 10; a pair of links 12 connecting said levers 151 to the upper knife-bar; a shaft 20 rotatably mounted in the frame of the machine; a pair of levers 21 mounted rigidly at 120 their lower ends upon said shaft 20; a pair of links 22 connecting said levers 21 to the lower knife-bar; a lever 9 mounted rigidly at its upper end upon said shaft 10; a driving-shaft;

an eccentric mounted upon said driving-shaft, a collar and link connecting said eccentric to the lower end of the lever 9; a counter-shaft a pair of engaging spur-gears mounted respectively upon said driving-shaft and counter-shafts; a lever 19 mounted rigidly at its upper end upon said shaft 20; a crank mounted rigidly upon said counter-shaft; a pitman connecting said crank to the lower end of said lever 19; and means for alternately intermittently oscillating said bars in a plane at right angles to the plane of the axes of the feed-rolls substantially as described and for the purpose set forth.

15 2. In a machine for folding or plaiting paper, the combination with the frame of the machine, of a pair of feed-rollers mounted one above the other in said frame; a pair of horizontal guideways formed one above the other at each side of said frame and extending toward said rollers; a pair of bars extending parallel to said rollers and supported at their ends in said guideways; a plaiting-knife secured rigidly to said upper bar and projecting toward the lower feed-roller; a second plaiting-knife secured rigidly to said lower bar and projecting toward the upper feed-roller; means for alternately reciprocating said bars; a driving-shaft, a gear mounted upon said shaft and having a laterally-projecting pin; means for intermittently oscillating the upper bar consisting of a bell-crank lever mounted rigidly upon one end of the upper bar, and having one arm projecting across the path of said pin, an adjustable link carried rigidly by the other arm thereof, a retractile coiled spring connecting the free end of said link to the frame of the machine; and means for intermittently oscillating said lower bar alternately with the oscillation of said upper bar and in a plane at right angles to the plane of the axes of the feed-rollers, substantially for the purpose set forth.

35 3. In a machine for folding or plaiting paper, the combination with the frame of the machine, of a pair of feed-rollers mounted one above the other in said frame; a pair of horizontal guideways formed one above the other at each side of said frame and extending toward said rollers; a pair of bars extending parallel to said rollers and supported at their ends in said guideways; a plaiting-knife secured rigidly to said upper bar and projecting toward the lower feed-roller; a second plaiting-knife secured rigidly to said lower bar and projecting toward the upper feed-roller; means for alternately reciprocating said bars; a driving-shaft, means for intermittently oscillating the said lower bar consisting of a cam mounted rigidly upon said driving-shaft, an arm mounted rigidly upon the adjacent end of the lower bar and adapted to be acted upon by said cam, and means for intermittently oscillating said upper bar alternately with the oscillations of the lower

bar, substantially as described and for the purpose set forth.

4. In combination with a pair of feed-rollers, a driving-shaft, an oval cam mounted upon said shaft, a stub-shaft, a ratchet-wheel and a gear-wheel mounted rigidly upon said shaft, a lever fulcrumed upon said shaft and carrying a spring-pawl to engage said ratchet-wheel the free end of said lever being engaged by said oval cam, and a retractile coiled spring connecting said lever to the frame, substantially as described.

5. In combination with a pair of feed-rollers, a driving-shaft, an oval cam mounted eccentrically upon said shaft, a stub-shaft, a ratchet-wheel and a gear-wheel mounted rigidly upon said shaft, a lever fulcrumed upon said shaft and carrying a spring-pawl to engage said ratchet-wheel the free end of said lever being engaged by said oval cam, and a retractile coiled spring connecting said lever to the frame, substantially as described.

6. In a machine for making plaited paper, the combination of means for plaiting the paper; a pair of rollers for feeding the plaited paper; a pair of rollers for feeding one or more binding-strips to said plaited paper; means for causing said binding-strips to adhere to said plaited paper; and means for operating said pairs of rolls and adapted to cause said strip-feeding rolls to feed a greater length than the paper fed by the paper-feeding rollers, for the purpose set forth.

7. In a machine for making plaited paper, the combination of means for plaiting the paper; a pair of rollers for feeding the plaited paper; a pair of rollers for feeding one or more binding-strips to said plaited paper; means for causing said binding-strips to adhere to said plaited paper; and a train of gears for operating said pairs of rolls and adapted to cause said strip-feeding rolls to feed a greater length than the paper fed by the paper-feeding rollers, for the purpose set forth.

8. In a machine for plaiting paper, the combination of the plaiting means, feeding-rollers, a conveyer consisting of a pair of receiving-rollers *e* located adjacent to the feeding-rollers, a pair of compressor-rollers *j*, *k*, located a short distance from said receiving-rollers, means for regulating the distance between said compressor-rollers, a series of loops independent of one another and each taking over one of said receiving-rollers and one of the compressor-rollers, a table-support inside the lower series of loops with its surface on a line with the tops of the lower rollers, a swinging table pivoted at one end adjacent to and on a level with the outer end of said table-support, a roller at the free end of said swinging table, for receiving the completed lining, a pair of rollers for feeding one or more binding-strips to the plaited paper; means for causing said binding-strips to adhere to said plaited paper; and means for driving the

rollers for feeding the strips, the conveyer, pressure-rollers, and the last-mentioned receiver-roller at a uniform speed and means for driving the main feed-rollers at a less speed, substantially as described and for the purpose set forth.

9. In a machine for plaiting paper, the combination of the plaiting means, feeding-rollers, a conveyer consisting of a pair of receiving-rollers *e* located adjacent to the feeding-rollers, a pair of compressor-rollers *j, k*, located a short distance from said receiving-rollers, means for varying the distance between said compressor-rollers, a series of loops independent of one another and each taking over one of said receiving-rollers and one of the compressor-rollers, a table supported inside the lower series of loops with its surface on a line with the tops of the lower rollers, a swinging table pivoted at one end adjacent to and on a level with the outer end of said table-support, a roller at the free end of said swinging table, for receiving the completed lining and means for driving said feeding-rollers, the conveyer and the last-mentioned receiver-roller at a uniform speed; a series of rollers each carrying a roller-strip of paper, means for coating one side of said strips with an adhesive compound, a pressure-roller extending transversely of the machine within the upper series of loops and

furnished with trunnions located in slots in the frame of the machine, substantially as described and for the purpose set forth.

10. In a plaiting-machine, a plaiting-knife 35 made up of a carrying-bar; a series of independent knife-sections arranged side by side, means for securing each of said knife-sections independently to said carrying-bar; a bar extending across said knife-sections near 40 their forward ends; and means for detachably rigidly connecting said knife-sections independently to said last-mentioned bar, substantially as described.

11. In a plaiting-machine, the combination 45 with the plaiting, feeding and binding mechanism, of driving mechanism therefor comprising a main driving-shaft and a stub-shaft, a pair of gears intermeshing with one another and mounted one on each of said shafts, a fly-wheel mounted upon said stub-shaft, tight and loose pulleys mounted upon said stub-shaft, and a belt for connecting said tight or loose pulleys to the initial source of power, substantially as and for the purpose set forth.

In testimony whereof I have affixed my signature in presence of two witnesses.

MATTHIAS KOCH.
